MOWER GUARD

James R. Sutherland, Minneapolis, Minn., assignor to
Viking Corporation, Minneapolis, Minn.

Filed July 9, 1964, Ser. No. 80,786

Term of patent 14 years

(Cl. D40—1)

FIG 1

FIG 2

FIG 3

FIG 4

FIG 5

FIGURE 1 is a top view of a new mower guard showing my new design;

FIGURE 2 is a right side elevation of the new mower guard with the left side elevation being a mirror image of the same;

FIGURE 3 is a rear end elevation of the same;

FIGURE 4 is a front end elevation of the same; and

FIGURE 5 is a bottom view of the same.

I claim:

The ornamental design for a mower guard, as shown and described.
